UNITED STATES PATENT OFFICE.

GILBERT S. THOMPSON, OF CEDAR RAPIDS, IOWA.

WATER-CLOSET FLUSH-TANK.

No. 813,599.

Specification of Letters Patent.

Patented Feb. 27, 1906.

Application filed June 14, 1904. Serial No. 212,561.

To all whom it may concern.

Be it known that I, GILBERT S. THOMPSON, a citizen of the United States, residing at Cedar Rapids, in the county of Linn and State 5 of Iowa, have invented certain new and useful Improvements in Water - Closet Flush-Tanks, of which the following is a specification.

The object of this invention is to improve 10 the construction of flush-tanks for water-closets, so as to render them more durable, convenient, and easily repaired.

The nature of the invention will clearly appear from the description and claims following, reference being had to the accompanying 15 drawings, in which—

Figure 1 is a front elevation of a flush-tank embodying my improvements, a part of the outer casing being broken away to show the 20 inner structure. Fig. 2 is a view from the rear and in perspective of the casing, a part of one corner being broken away to show details of the valve-trip. Fig. 3 is a perspective view of the inner tank with one side removed to show the construction of the metal 25 lining.

In the construction of water-closet flush-tanks it is common to provide a finished hard-wood tank lined with sheet-copper double-seamed at the corners and the seams soldered. 30 In the case of low-down tanks the tank is provided with a cover; but the high tanks are usually left open. A frequent difficulty met with in connection with such tanks is 35 the natural tendency of dampness to collect between the metal lining and the wood casing, especially in hot weather. This inner dampness (due to the "sweating" of the cooler inner lining) and the outer heat and 40 dryness tend very soon to open the joints of the casing, greatly marring its appearance if not destroying its utility. Another difficulty arises from the fact that electrolysis is very 45 apt to destroy the solder on a copper tank-lining, and a leak soon takes place. This invention is designed to remove these difficulties, as will be apparent from the description following.

Referring to the drawings, A is a tank, 50 which may be a cheap and simple box made of soft wood open at the top. This is lined, preferably, with a seamless lining of sheet metal, preferably copper. The lining is formed of a single sheet, folded at the corners 55 in a well-known way, flanged over at the

edges B, and nailed to the upper edge of the tank. The lining C needs no solder and is practically indestructible.

To the ends of the tank are attached brackets or cleats D and E, the former being 60 wide enough to furnish a ledge extending outside of an outer service-pipe F. This is carried up to the top of the tank, near the back side, and attached thereto by a flanged elbow G. To this connects an angle-valve H, and 65 from this a down-pipe I extends down as far into the tank as desired. Through a hole J in the bracket D runs a rod K, connecting with the valve-lever L. At its lower end the rod is bent laterally, so as to engage a pin M, 70 provided with a suitable button N and adapted to slide a limited distance in an adjacent part of the outer case P, which has a slot Q therein to take said pin. The outer case is made open on two sides, the back and bottom, and is made large enough to slip easily over the entire tank and its connections, completely hiding them from view. It is provided with internal cleats R to engage those 75 at the ends of the inner tank. These cleats are preferably inclined, as shown, so that the weight of the outer casing tends to make it fit tightly against the wall back of the tank. When in position, the pin M projects inwardly just over the lateral bend in the trip- 80 rod K, and a downward push on the button N operates to flush the closet, as will be understood.

The outer casing may be as costly and as highly finished as desired without danger of 85 opening joints, since there is no direct contact of moisture with it, inside or outside. It also obviates danger and injury in setting or repairing the tank, inasmuch as it may be 90 set aside when any work is being done on the tank.

A further advantage incidental to this construction is that the dealer may exhibit a great variety in design or finish of cases without the expense of tanks and connections for 95 each, a single tank serving for the display of all, provided, of course, that all are of the same size.

Having thus described my invention, what I claim as new, and desire to secure by Letters Patent, is—

1. The combination of a permanent flush-tank forming a cistern for water not under pressure, suitable feed and discharge pipes therefor, and a removable ornamental cas- 110

ing therefor adapted to inclose and conceal the water-tank on all sides except the back and bottom.

2. In a flush-tank, the combination of a water-tank provided with supports for an outer casing, a removable outer casing, and cleats thereon to engage said supports.

3. In a flush-tank, the combination of a water-tank, a removable outer casing therefor, and inclined cleats to support the casing on the tank and close to the wall behind it.

4. The combination with a permanent water-tank forming a cistern for water not under pressure, suitable feed and discharge

pipes therefor, a removable ornamental casing for said tank, adapted to cover and conceal the same on all sides except the back and bottom, supporting-cleats for said casing inside thereof, and engaging cleats on the tank, the feed or service pipe passing up between the tank and casing, and discharging into the tank at the top.

In testimony whereof I affix my signature in presence of two witnesses.

GILBERT S. THOMPSON.
